UNITED STATES PATENT OFFICE

GEORGE G. GOING, OF MIDDLETOWN, CONNECTICUT, ASSIGNOR, BY MESNE ASSIGNMENTS, TO REMINGTON TYPEWRITER COMPANY, A CORPORATION OF NEW YORK

TYPEWRITING MACHINE

Application filed April 19, 1927. Serial No. 184,929.

My invention relates to typewriting and like machines and more particularly to line spacing mechanism therefor.

One of the main objects of my invention, generally stated, is to provide an improved line spacing mechanism having a comparatively simple construction which may be manufactured at small cost, but which nevertheless is highly efficient in use. 10 A further object of my invention is to provide an improved line spacing mechanism which is simple in construction and can be readily set to provide not only for the selection of standard spacing of the 15 extent of say, one, two and three minimum spaces, but may also be adjusted to provide for a variation from such spacing, as, for example, to provide for effecting at each actuation an irregular extent of line spacing corresponding to, say, 1½ or 2½ minimum line spaces, as may be desired.

To the above and other ends which will hereinafter appear, my invention consists in the features of construction, arrangements 25 of parts and combinations of devices set forth in the following description and particularly pointed out in the appended claims.

In the accompanying drawings wherein like reference characters designate corresponding parts in the different views:

Figure 1 is a fragmentary, detail, enlarged, top plan view showing one end of a carriage of a typewriting machine equipped with the devices of my invention.

Figure 2 is an enlarged, detail, fragmentary, vertical sectional view of the same with parts omitted, the section being taken on the line 2—2 of Fig. 1 and looking in the direction of the arrows at said line.

Figure 3 is an enlarged, detail, transverse sectional view of the structure taken on the line 3—3 of Fig. 1 and looking in the direction of the arrows at said line.

Figure 4 is a view corresponding to Fig. 1, but showing the parts in front elevation.

Figure 5 is a detail plan view of the sheet metal blank from which the line spacing pawl-carrier is formed.

Figure 6 is an enlarged, detail, perspec-

tive view of the line spacing regulator or shield shown detached.

Figure 7 is a detail, fragmentary, top plan view, with a part sectioned away, of the pawl-carrier and the spring mounted thereon. 55

Figure 8 is an enlarged, vertical sectional view of the carriage taken on the line 8—8 of Fig. 4 and looking in the direction of the arrows at said line. 60

Figure 9 is an enlarged, detail, fragmentary perspective view of the line spacing wheel and the detent therefor.

I have shown my invention embodied, in the present instance, in the carriage of a 65 No. 6 Remington-noiseless machine. While the devices of my invention may be readily incorporated in such machine without modifying, or materially modifying, other structural features thereof, it should be understood that the invention is not restricted to employment in said machine but is of general application and may be employed in various styles of typewriting and like machines wherever found available. 70

In the present instance the carriage comprises a supporting rail or bar 1 to which end plates 2 are secured by screws 3. These end plates are also connected by suitable cross bars, one of which is indicated at 4. 75 The carriage rail 1 is grooved on opposite sides, as indicated at 5, to receive anti-friction rollers that in turn travel in grooved rails in the case shift frame, not shown. The usual means (not shown) are also employed 80 in the rear of the carriage, which with the means described support the carriage for case shift movement as well as for letter space traveling movement under control of the usual letter space mechanism, not shown. 85

A cylindrical platen 6 is supported in the ordinary manner for rotative line space movement in bearing openings in the end plates 2 of the carriage. The left-hand hub 7 of the platen extends through a bearing opening in the associated end plate and is normally connected by the usual platen clutch (shown in part in Fig. 8) with a line spacing wheel 8. 90

Ordinarily, heretofore, the teeth of a line 100

spacing wheel are such as to provide for the use of one tooth for the minimum line space to be effected, so that the line spacing wheel is shifted the extent of one tooth for single spacing, two teeth for double spacing, and three teeth for triple spacing, in accordance with the adjustment of the line space regulating device. By my present invention I provide for single, double and triple spacing as heretofore, and also provide for line spacing the platen irregular distances, such for example as providing for line spacing the platen the distance of $1\frac{1}{2}$ or $2\frac{1}{2}$ minimum line spaces, as may be desired. Therefore, the operator may set the regulator to provide for spacing the platen the extent of 1, $1\frac{1}{2}$, 2, $2\frac{1}{2}$ or 4 minimum line spaces, as desired. This is accomplished by the simple expedient of separating the teeth of the line spacing wheel an aliquot part of a minimum line space, and providing for the use of a plurality of teeth for the minimum line space produced on the machine and controlling the pawl to move the platen the distance of an odd or even number of teeth, as two, three, four, five or six teeth. In the particular example shown I provide sixty line spacing teeth 9 on the line spacing wheel, instead of thirty, as heretofore, and provide regulating means which may be set to enable the line spacing pawl to engage said teeth sooner or later in the effective stroke of the pawl, and thus shift the wheel and platen the extent of two, three, four, five or six teeth of the wheel, as may be desired.

The mechanism for controlling the wheel will now be described.

A detent roller 10 engages the teeth of the wheel and is carried by a spring-pressed carrier, designated as a whole by the reference numeral 11. This carrier is preferably made of sheet metal and is bent so as to be substantially U-shaped in cross section, providing side walls 12 united by a rear connecting wall 13. The detent roller is received between the side walls 12 at the upper end thereof, and is supported thereby on a pivot 14. The side walls 12 at the lower ends thereof are provided with bearing openings that receive a pivotal support 15. The support 15 bears at one end against a washer 16^a and is in the nature of an eccentric. That is to say, the member 15 has an eccentrically disposed opening therethrough that receives the stem of a headed binding screw 16 on which the eccentric may receive a turning adjustment to different set positions. The rear end of the screw 16^a is threaded into a tapped opening in the companion end plate 2. When the screw is tightened it will firmly hold the eccentric or pivotal support 15 in the rotative position to which it has been adjusted with the

aid of a hexagonal head 17 thereon. This provides a pivotal support for the detent, and one which may be adjusted to vary the position of the detent roller to accord with the position of the engaged teeth of the wheel at the end of the throw of the line spacing pawl. A coiled expansion spring 18 bears at one end against the connecting wall 13 of the carrier 11. The other end of this spring is seated in a recess 19 in a spacing collar 20 provided with reduced hubs 20^a. Said collar is interposed between a depending arm 21 of a supporting bracket, designated as a whole by the reference numeral 22, and the associated end plate 2 of the carriage. This collar 20 is held in place by a headed screw 23, the stem of which passes through registering openings in the arm 21 and in the collar. The inner end of the screw is threaded into a tapped opening in the end plate, and when tightened constitutes a support for the bracket and also firmly binds and holds the collar in place.

The line spacing pawl 24 is provided with a hook-like engaging nose 25 which coacts with the teeth of the line spacing wheel and is pivoted at one end on a pivot pin 26 carried by a line spacing pawl-carrier, designated as a whole by the reference numeral 27. This carrier is preferably struck up from a single piece of sheet metal, the blank for the carrier being shown in Fig. 5. This carrier is formed from a single piece with two parallel side arms 28 bent up on the dotted lines indicated in Fig. 5. These arms are united at their ends and lower edges by two integral cross pieces 29 and 30. Formed integral with one of the side arms 28 at the upper edge thereof is a cross piece or extension 31 which extends across the opening between and overlies the arms 28 of the carrier. The cross piece or member 30 has a forward extension 32 for connection with the line spacing lever, as will presently appear. The line spacing pawl is pivoted between the side arms 28, extending forward and downward therefrom. The pivot 26 on which the pawl is mounted is riveted at one end to one of said side arms 28 and is seated at its other end in a registering opening 33 in the other side arm.

A spring for forcing the pawl around its pivot towards the line spacing wheel is carried by the carrier 27. In the present instance this spring is a leaf spring 34 formed with a T-shaped head 35 and lateral side enlargements 36. The upper edges of the side arms 28 have recesses 37 in the rear of the cross piece 31. Each of these recesses has a depth corresponding substantially to the thickness of the spring, and the fore-and-aft dimensions of each recess corresponds substantially to the width of an arm 35 of the cross head of the spring. This provides

seats in which the cross head 35 may be received and firmly held against movement in any direction in the plane of the cross head. In this connection it will be observed that 5 the enlargements 36 of the spring coat with the inner side walls of the arms 28 of the carrier, whereas, the sides of the reduced free end portion of said spring are free from contact with the carrier. It will be seen that 10 the force of the spring forward of its cross head is at all times directed upward against and resisted by the cross piece 31 on the carrier, causing the cross head at all times to be forced down in its seat, thus firmly though 15 detachably anchoring one end of the spring to the carrier without any additional means. These means enable the spring to be readily connected to its carrier or support, and enables a broken or damaged spring to be readily 20 replaced with a new one. For example, in order to connect a spring it is merely necessary to slip the free end of the spring from the rear beneath the arm 31 and force the spring forward until the anchoring head 25 35 seats itself in the recesses 37, and the spring is connected.

The carrier 27 is located above and is mounted for fore-and-aft movement on the supporting bracket 22, and overlies the line spacing wheel, being substantially in the plane thereof. Thus, the rear end portion of the carrier has its side arms 28 slotted longitudinally at 38 to receive a supporting pin 39. The supporting pin, as shown in 30 Fig. 3, is in the nature of a shouldered, headed screw received at its threaded end in a tapped opening in an arm 40 on the bracket 22. The threaded end of the screw extends beyond the bracket arm 40 and receives a shouldered lock nut 41. In this 35 manner the rear end of the carrier is supported for substantially rectilinear sliding movement fore-and-aft of the machine on the pin 39. The forward end or extension 40 45 32 of the carrier is apertured at 42 (see Fig. 5) to receive a pivot pin 43 which is riveted to said extension. This pivot pin is received in a bearing opening in an arm 44 of a line spacing lever to pivotally connect 50 the lever arm with the carrier 27 at the forward end thereof. The other, hand controlled, arm 45 of the line spacing lever extends forward, the lever as a whole being mounted to turn on a headed pivot screw 46 55 on the bracket 22, said pivot having a vertically disposed axis. As the lever arm 45 is swung from left to right it not only actuates the line spacing mechanism but returns the carriage to the right. In the movement of 60 the lever around its pivot the point of pivotal connection 43 travels fore-and-aft of the machine substantially in the plane of the escapement wheel, and a corresponding longitudinal sliding movement is transmitted to the carrier 27.

A depending pin 47 on the line spacing lever passes down through a segmental slot 48 in the bracket 22. Beneath the bracket a coiled, contractile, returning spring 49 is connected at one end to the pin 47 and at the other end to a pin 50 carried by a bracket 51 connected to the bottom of the bracket 22. The spring 49 returns the line spacing lever and the parts connected therewith to normal position, the pin 47 engaging one end 70 75 wall of the slot and limiting the return motion of the parts.

In order to determine at what point in the effective throw of the line spacing pawl it shall engage the teeth of the line spacing wheel, and thus determine the extent of line spacing movement of the wheel, I have provided an adjustable line space regulating device which is shown detached in Fig. 6. This device, designated as a whole by the reference numeral 52, is preferably made of sheet metal. The main body portion of the device is recessed at 53 to provide a segmental bearing portion that is seated on the platen clutch housing 54 arranged concentrically 80 85 with the platen and connected to turn therewith.

In order to provide an additional support for the device 52, and to guide it in its adjustment around the axis of the platen, I 90 provide a sheet metal guide 55 riveted at 56 to the bracket arm 21. This guide is formed with a central finger 57 bent in one direction from the body thereof in order to embrace the device 52 on one side thereof, 95 and is provided with two fingers 58 bent in the opposite direction to embrace the device 52 on the opposite side thereof. In addition I provide a segmental slot 59 in the device 52, and through this slot extends a shouldered screw or bolt 60 headed at one end, 100 as at 61, and threaded at the other end to coat with a nut 62, the unthreaded shouldered portion of the screw passing through the slot 59. This screw passes freely 105 through an opening in a depending arm 63 on the bracket 22, the nut 62 being on the outside of the arm 63 and the head 61 co-acting with the inner face of the device 52, thus acting to guide and support said device 110 from opposite sides without unduly clamping it against the bracket arm 63, so that the device 52 is free to be adjusted. The device 52 has an offset curved flange 64 115 projecting therefrom which extends over the teeth of the line spacing wheel and is concentric with the axis of said wheel and the platen. The engaging nose 25 of the line spacing pawl normally rests on the flange 64 as shown in Fig. 8, the flange acting as an 120 adjustable shield over which the pawl slides in its line spacing movement. When the pawl rides off the shield it will engage a tooth of the line spacing wheel and turn the wheel and platen the required distance 125 130 de-

pending on the position of adjustment of the regulator 52 and its shield 64.

In order to provide for an adjustment of the device 52 to different positions where it will afford a line spacing movement at each actuation of the pawl for the extent of two, three, four, five or six teeth of the wheel, I provide detent mechanism which in the present instance is as follows:

- 10 An arm 65 is pivoted at one end on the reduced end 66 of the lock nut 41 (see Fig. 3) being confined between the head of said nut and the bracket arm 40. The free end of this arm carries an outwardly extending pin 67 which projects through a slot 68 in the member 52. The lower wall of this slot is provided with five depressions 69, 70, 71, 72 and 73 in any one of which the pin 67 may be seated to hold the line space regulating device 52 in a corresponding position of adjustment. A contractile spring 74 is connected at one end to the guide 55 and at its other end to said arm 65, and exerts its force to maintain the pin 67 seated in any 25 of the depressions in which it may be received, such force being exerted to move the pin towards the axis of the platen. A finger piece 75 projects laterally from the regulating device 52 to facilitate its adjustment. Extending laterally from the upper edge of the device 52 is a flange 76 with indices, such for example as the numerals "1," "2," "3," "4" and "5" with corresponding registering scale marks, each index being situated above one of the locking depressions in which the pin 67 is received. It will be understood that an adjustment of the regulating device to bring any given index thereon into register with the pin 67 30 will cause the shield 64 to be set to afford a corresponding line spacing movement of the wheel for the extent of two, three, four, five or six teeth of the wheel, for spacing 1, $1\frac{1}{2}$, 2, $2\frac{1}{2}$ or 3 line spaces respectively, depending on such adjustment.

In order to prevent an overthrow of the line spacing wheel and platen, I provide an extension 77 on the free end of the line spacing pawl which terminates in a contact 50 78. The free end of the pawl takes a curvilinear movement during its line spacing operation from the dotted to the full line position in Fig. 2, and the contact 78 on the pawl will always be brought into contactive engagement with the bottom of the supporting bracket 22 at the end of the stroke, as shown in full lines in Fig. 2. This results in positively and effectively locking the nose 25 of the pawl in engagement with 55 the teeth of the wheel and preventing an overthrow of the wheel and platen.

The single-piece sheet metal bracket 22 is secured to the carriage by screws 79 and 80 in addition to the screw 23.

65 It will be understood that aside from the

capability of adjusting the line space regulating device 52 to the five positions indicated, instead of adjusting it only to the three positions indicated by the index numerals "1," "2" and "3," the construction may be employed in connection with a standard line spacing wheel in which one tooth is used for each minimum line space employed. In such case the substitution of a regulating device having only the three 75 points of adjustment indicated above may be readily effected.

From the foregoing description it will be understood that I have provided a comparatively simple, inexpensive and sturdy 80 construction in which nearly all of the parts are struck up from sheet metal; which affords irregular as well as regular line spacing and which is highly effective in use.

Various changes may be made in the construction, and parts thereof may be employed without others, without departing from my invention as it is defined in the accompanying claims.

What I claim as new and desire to secure by Letters Patent, is:—

1. The combination of a line spacing wheel; a line spacing lever; a pawl carrier overlying said wheel and supported at its rear end substantially in the plane of said wheel for approximate rectilinear sliding movement fore-and-aft of the machine and having at its forward end a pivotal connection with an arm of said lever, said carrier comprising a single piece of sheet metal formed with two connected parallel side arms; a line spacing pawl located between and pivoted to said arms; and a supporting bracket for said lever and carrier and with which the free end portion of the pawl engages during the operating stroke in order to lock the pawl in engagement with the teeth of the wheel at the last part of the operating stroke and prevent overthrow of the wheel.

2. The combination of a line spacing wheel, a pawl therefor, a leaf spring for pressing said pawl towards the wheel, and means for attaching the spring to its support, said means comprising a T-shaped 115 anchoring head on the spring, arms on the support spaced apart to receive the body of the spring and having open mouth recesses in which said head is adapted to be seated, and a cross connection between the arms of 120 said support overlying the body of the spring intermediate said head and the free end of the spring and which resists the outward pressure of the spring and holds the cross head seated in said recesses.

3. The combination of a carriage, a line spacing wheel, a line spacing lever, a pawl carrier actuated thereby and having substantially a rectilinear operating movement, a line spacing pawl pivoted to said car- 125

rier, the free end portion of the pawl moving in a curved path in its engagement with the line spacing wheel, a supporting bracket by which said carrier and line spacing lever are supported and with the body portion of which the free end portion of said pawl contacts at the last part of its effective stroke to lock the pawl in engagement with the teeth of the wheel and prevent overthrow of the platen, said supporting bracket together with the parts carried thereby being detachable as a single unit from the carriage.

4. The combination of a line spacing wheel; a line spacing lever; a pawl carrier overlying said wheel and supported at its rear end in the plane of said wheel for approximate rectilinear sliding movement fore-and-aft of the machine and connected at its forward end by a pivotal connection with an arm of said lever, said carrier comprising two connected parallel side arms arranged above and substantially in the plane of said wheel; and a line spacing pawl located between and pivoted to said arms and wholly in the plane of said wheel and extending down therefrom for engagement with said line spacing wheel during the rearward movement of said carrier.

5. The combination of a line spacing wheel; a line spacing lever; a pawl carrier overlying said wheel and supported at its rear end in the plane of said wheel for approximate rectilinear sliding movement fore-and-aft of the machine and having at its forward end a pivotal connection with an arm of said lever, said carrier comprising two connected parallel sheet metal side arms arranged above and substantially in the plane of the wheel; a line spacing pawl located between and pivoted to said arms and in the plane of the line spacing wheel; and a leaf spring anchored at one end to said carrier and extending at its free end down between the side arms thereof and pressing the engaging end of the pawl towards the line spacing wheel.

Signed at Middletown, in the county of Middlesex, and State of Connecticut, this 14th day of April, A. D. 1927.

GEORGE G. GOING.
